UNITED STATES PATENT OFFICE.

FRANK PFOUS, OF COSHOCOTON, OHIO, ASSIGNOR TO AMERICAN LEAD PENCIL COMPANY, OF NEW YORK, N. Y., A CORPORATION OF NEW YORK.

DESIGN FOR A DISPLAY CABINET.

Application filed November 8, 1922. Serial No. 4,238. Term of patent 7 years.

To all whom it may concern:

Be it known that I, FRANK PFOUS, a citizen of the United States, residing at Coshocton, in the county of Coshocton and State of Ohio, have invented a new, original, and ornamental Design for Display Cabinet, of which the following is a specification, reference being had to the accompanying drawing, forming part thereof.

Fig. 1 is a front view of the display cabinet, containing my new design; and

Fig. 2 is a side elevation of the same.

I claim:—

The ornamental design for a display cabinet, substantially as shown.

In testimony, that I claim the foregoing as my own, I have hereto affixed my signature.

FRANK PFOUS.
